CLAIM

The ornamental design for a animal face bath tub, as shown and described.

DESCRIPTION

FIG. 1 is a front perspective view of the animal face bath tub showing my new design with a lid placed on top of the tub; FIG. 2 is a front perspective view thereof with the lid removed;

FIG. 3 is a rear perspective view thereof with a lid showing a drain plug;

FIG. 4 is a rear perspective view thereof with lid removed showing a drain plug;

FIG. 5 is a front elevation view thereof having an example of an animal animated face illustrated in broken lines;

FIG. 6 is a rear elevation view thereof;

FIG. 7 is a left side elevation view the right side being a mirror image thereof;

FIG. 8 is a top plan view thereof with lid; the bottom surface is not illustrated as it forms no part of the claimed design.

FIG. 9 is a top perspective view thereof with lid;

FIG. 10 is a front elevation view thereof having another example of an animal animated face illustrated in broken lines;

FIG. 11 is a front elevation view thereof having still another example of an animal animated face illustrated in broken lines; and,

FIG. 12 is a front elevation view thereof having yet another example of an animal animated face illustrated in broken lines.
